BENCH

Robert S. Wormser, Hillsdale, Mich., assignor to Game-Time Inc., Litchfield, Mich., a corporation of Michigan

Filed Mar. 4, 1968, Ser. No. 10,829

Term of patent 14 years

U.S. Cl. D15—11
Int. Cl. D6—01

FIG. 1

FIG. 2

FIG. 4

FIG. 3

FIG. 1 is a perspective view of a bench in accord with my new design,

FIG. 2 is a side elevational view of the bench, the opposite side being of identical appearance,

FIG. 3 is an end elevational view of the bench of my design, the opposite end being identical thereto, and

FIG. 4 is a top plan view.

I claim:

The ornamental design of a bench, substantially as shown and described.
